CONVERSION OF CONTINUOUS FILAMENTS
INTO YARN CONTAINING STAPLE FIBER

William Ivan Taylor, Spondon, near Derby, England, assignor to Celanese Corporation of America, a corporation of Delaware

Application March 3, 1936, Serial No. 66,868
In Great Britain March 6, 1935

1 Claim. (Cl. 19—1)

This invention relates to a method and apparatus for the conversion of continuous filaments directly into yarn containing staple fiber.

According to the invention, a bundle of filaments is caused to pass between two positively driven surfaces moving in the same general direction as the filaments, at least one of them, however, having a peripheral speed different from the speed of the filaments, and preferably also from the other, at least one of the surfaces being driven through flexible means permitting the two surfaces to be pressed against each other with but light pressure, and yet at the same time allowing the surfaces to move at predetermined speeds. At least one of the surfaces has a cutting action, so that by reason of the passage of the filaments between the surfaces and the light pressure exerted between the surfaces, the filaments in the bundle are transformed into staple fibers, and the filaments leave the surfaces as yarn containing staple fiber.

The operation of converting continuous filaments in the bundle into staple fibers as described above does not substantially affect the degree of twist which the bundle may possess. However, when the bundle has little or no twist, the product should be collected, after the conversion of the filaments into staple fibers, by a twisting and winding operation to impart to it a twist which may be the amount of twist required in the final product, or may need to be augmented by further twisting. In either case, the twist so imparted during winding maintains the coherence of the product. Alternatively, the coherence may be maintained by reason of a substantial initial degree of twist in the continuous filament bundle, which twist, as previously stated, is practically unaffected by the conversion.

The surfaces should together make pressure contact preferably substantially at a point in the length of the bundle, but while a pair of rollers may most conveniently be employed for this purpose other arrangements may be adopted, e. g. a roller operating against a band. The following description will for simplicity be directed solely to arrangements of apparatus using rollers to provide both surfaces.

In all cases the difference of speed between the two surfaces which are pressed together should be adjusted in accordance with the nature of the material under treatment and the characteristics desired in the final product. The invention permits the necessary adjustment of speed to be effected while allowing substantially independent control of the pressure exerted between the sur-

faces to be maintained, and so readily permits the use of greater or less pressure where necessary, as with the treatment of bundles of greater or less denier.

Other factors governing the nature of the final product, which factors may be varied as required, are the nature of the cutting surface, the speed of progression of the filament bundle through the apparatus, the difference between the speed of the surface or surfaces and the filaments, the fineness of the individual filaments in the bundle, and the amount of twist in the bundle.

The cutting surface may be of an abrasive nature, e. g. a roller surfaced with or made of abrasive material. It is, however, advantageous to employ a cutting roller provided with fine sharp-edged flutes running either helically or substantially parallel to the axis of the roller, a roller of this type providing for greater control over the properties of the final product. Both surfaces may have a cutting action, for example a pair of fluted cutting rollers may be used, the flutes of the two rollers running in such directions as to cross each other at the point of contact between the rollers. One roller, however, may have a plain surface.

It is advantageous to allow the weight of one of the rollers to provide the necessary light pressure between the surfaces, whether such pressing roller has or has not a cutting action.

The invention is applicable to the treatment of different kinds of continuous filaments, e. g. cellulose derivative filaments such as cellulose acetate filaments, cellulosic filaments such as viscose filaments, and natural silk filaments.

By way of example, a form of apparatus provided with driving means according to the invention will now be described in greater detail with reference to the accompanying drawing in which

Fig. 1 is a side elevation of an apparatus driven by means according to the present invention for converting a bundle of continuous filaments into a staple fiber yarn, and

Figs. 2—5 give alternative forms of the driving mechanism according to the present invention.

In Fig. 1 the apparatus is shown as comprising generally two pairs of rollers 1, 2, 3, 4, the rollers 1 and 3 being mounted on positively driven shafts 5 and 6 while the rollers 2 and 4 are carried on a bracket 7 suspended from a stationary shaft 8 above the rollers. The roller 2 is carried in slotted bearings 9 in a member 10 secured to the bracket 7 by means of a nut and bolt 11 passing through a slot 12 in the bracket 7 so that the position of the member 10 may be adjusted vertically.

The roller 4 is mounted in bearings carried in a slot 13 in the lower end of the bracket 7.

Yarn 14 consisting of continuous filaments is supplied horizontally to the upper pair of rollers 1, 2 and passing over the roller 1 proceeds downwards to the rollers 3, 4. The roller 3 is grooved so that it grips the filaments with the aid of the roller 4 and is driven at a higher speed than the roller 1. In consequence the bundle of continuous filaments 14 is caused to slip over the surface of the roller 1. The roller 1 is provided with flutes making sharp edges with the surface of the roller so that the roller 1 exerts a cutting action on the filaments and converts the bundle of continuous filaments 14 into a continuous bundle of staple fibers 15. This bundle proceeds downwards to the guide 16 of a cap-spinning device 17 by means of which it is twisted and spun into a staple fiber yarn and wound on the package 18 which is driven by means of the band 19.

In order to bring about the cutting of the continuous filaments in the bundle 14 between the rollers 1 and 2 the roller 2 is allowed to press downwards on the roller 1 with its own weight, a clearance 20 being allowed at the bottom of the slotted bearing 9 to permit the weight of the roller 2 to be effective. The roller 2 is positively driven at a speed which may be the same as, or different from, that of the roller 1 by means of a flexible driving shaft 21 attached at one end to the roller 2 and having at the other end a bevel gear 23 engaging with a bevel gear 24 on a driving shaft 25. The shaft 25 is driven in any desired speed relationship with the shafts 5, 6 so that the speed of the roller 2, like those of the rollers 1 and 3, is positively controlled. The flutes in the surface of the roller 1 by means of which the filaments, pressed into sliding contact with the roller 1, are periodically severed to form staple fibers, are shown more clearly at 26 in Figs. 2-5.

In Figs. 2 and 3 means are shown for driving the roller 2 from the roller 1. In Fig. 2 gear wheels 27, 28 are secured to the rollers 1 and 2 respectively. The teeth of the gear wheels 27 and 28 are longer than is usual so that any vertical movement of the roller 2, which is freely allowed by the slotted bearings 9, does not interfere with the driving of the roller 2. The gears 27 and 28 are equal in size so that the rollers 1 and 2 are driven at equal speeds. In Fig. 3 gear wheels 29 and 30 are shown which are different in size, the gear wheel 29 being smaller than the gear wheel 30 so that the roller 2 is driven more slowly than the roller 1.

In Fig. 4 a further method of driving the roller 2 from the shaft 5 of the roller 1 is shown, in which the shaft 5 is provided with a bevel gear 31 engaging with a bevel gear 32 carried on a

countershaft 33 mounted in bearings 34, 35. Splined to the countershaft 33 is a friction wheel 36 which is held downwards against a spring 37 on the shaft 33 by means of a lock nut 38 engaging on a screwed portion 39 of the shaft 33. The friction wheel 36 engages with a friction disc 40 secured to the shaft 41 of the roller 2. By these means the roller 2 is driven from the shaft 5 of the roller 1 and the speed ratio between the roller 2 and the roller 1 may be adjusted by means of the locking means 38 with the aid of which the friction wheel 36 may be caused to engage with any desired radius of the friction disc 40.

In Fig. 5 another form of apparatus is shown in which the roller 2 is driven independently of the roller 1 from a shaft 42. Between the positively driven shaft 42 and the shaft 41 of the roller 2 are interposed coupling means comprising two discs 43, 44 secured to the ends of the shafts 41 and 42 respectively, the discs being provided with feathers 45, 46 respectively proceeding diametrically across their faces. The two feathers 45, 46 engage in diametral grooves in an intermediate disc 47 by means of which the two discs are coupled together. The two grooves which are disposed on opposite faces of the disc 47 are at right angles to one another. By means of this coupling, while the roller 2 is positively driven at the same speed as the shaft 42 it is free to rise and fall in the slotted bearings 9 if caused to do so by the filaments 14 passing between the rollers 1 and 2.

Having described my invention, what I desire to secure by Letters Patent is:—

Apparatus for the production from a bundle of continuous filaments of a continuous product containing staple fibers, said apparatus comprising a pair of rollers, one at least of said rollers having a cutting surface, means for drawing a bundle of continuous filaments through said pair of rollers at a speed different from the peripheral speed of at least one of said rollers, means for pressing said rollers together so as to exert a light pressure upon the bundle of filaments passing between them, a driving shaft positively connected to one of said rollers, a further driving shaft and a coupling including discs secured to said further shaft and said other roller, diametrically disposed feathers on the faces of said discs, and an intermediate disc between said discs, said intermediate disc being diametrically slotted to receive said feathers, the slots being at right angles to one another and on opposite faces of said intermediate disc, said coupling being adapted to allow variation in the distance apart of the axes of rotation of the two rollers without interruption of the drive.
